[57] CLAIM

The ornamental design for a video cassette storage rack, as shown and described.

DESCRIPTION

FIG. 1 is a perspective view of a video cassette storage rack showing our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right end elevational view thereof, the left end being substantially a mirror image thereof; and

FIG. 7 is a cross sectional view taken along line 7—7 of FIG. 2.

FIG. 1

FIG. 2

FIG. 3

FIG. 4

FIG. 5
